DATA-ENTRY STATION FOR AUTOMATIC DATA PROCESSING

Charles A. Pycha and Frank Wilkey, Jr., Rochester, Minn., assignors to International Business Machines Corporation, Armonk, N.Y.

Filed Mar. 22, 1973, Ser. No. 344,001

Term of patent 14 years

Int. Cl. D14—02

U.S. Cl. D26—5 C

FIG. 1

FIG. 2

FIG. 1 is a front perspective view of a data-entry station for automatic data processing, showing our new design;

FIG. 2 is a bottom plan view thereof.

The rear and left sides of said data-entry station are identical in appearance to the front and right sides, respectively, shown in FIG. 1.

We claim:

The ornamental design for a data-entry station for automatic data processing, as shown and described.
